ADJUSTING SLEEVE

Edward J. Herbenar, Detroit, Mich., assignor to
 Thompson Products, Inc., Cleveland, Ohio, a
 corporation of Ohio

Application April 3, 1951, Serial No. 218,978

1 Claim. (Cl. 287—60)

1

The present invention relates to improvements in an adjusting sleeve or turnbuckle barrel. More specifically, the invention relates to an adjusting sleeve and an adjusting sleeve assembly in which the gripping action about connected members is substantially improved while the assembly of split clamping rings on the slotted tube ends is simplified.

Most adjusting sleeve assemblies of the prior art are of the type requiring the placing of the clamps on the slotted tube ends in a particular radial relation in order that the clamping effect will not be reduced. Furthermore, the clamping action occurring in these assemblies is, to a great extent, a hinging or pivoting of each peripheral half of the slotted end portion about a line diametrically opposite to the slot, thus applying an uneven pressure to the connected members. Because of the use of a longitudinal slot, the clamping action in these prior art turnbuckles was attained by straight frictional engagement between the threads of the turnbuckle and the connected members without any wedging therebetween. In addition, many of the adjusting sleeves of the prior art are more expeditiously formed from flat sheet stock than from tubular stock.

According to the present invention, an internally threaded adjusting sleeve is provided with spiral or helical slots in the end portions. Clamping rings of any suitable construction are inserted over the slotted end portions for contracting the same about portions of two connected members inserted within the tube. The use of helical slots permits the formation of longer slots to give a superior clamping effect without reducing the strength of the tube. The clamping rings can be placed in any radial position on the circumference of the tube without reducing the locking effect. Because of the helical formation of the slots, a substantially improved wrap-around of the slotted end portion is achieved, and the tendency to hinge about a fulcrum diametrically opposite to a longitudinal slot is eliminated. Furthermore, the internal threads of the slotted end portions tend to wedge against the threads of the connected members by the torsional strains set up due to pivoting of the material of the end portions about the inner ends of the slots, thereby providing a substantially superior attachment with a reduced clamping force. Since no external protuberances or other integral extensions are provided on the tube, this member can be formed either from flat sheet stock or from tubular stock with equal ease.

2

It is, therefore, an object of the present invention to provide an improved adjusting sleeve.

Another object of the invention is to provide a simplified adjusting sleeve assembly having an increased clamping effectiveness.

A further object of the invention is to provide an adjusting sleeve utilizing relatively long helical slots to increase the clamping effect without reducing the strength of the sleeve.

10 Still another object of the present invention is to provide a turnbuckle barrel assembly in which the clamping members can be placed in any radial position on the circumference of the slotted barrel ends without reducing the locking effect.

15 A still further object of the invention is to provide an adjusting sleeve assembly in which hinging about a line diametrically opposite to the slot is substantially eliminated to increase the clamping efficiency.

20 Yet another object of the invention is to provide an adjustable clamping sleeve assembly in which the clamping effect is substantially increased while the clamping force required is substantially decreased, at least partially due to a wedging action between mating threads on the sleeve and the connected member.

Other objects, features and advantages of the present invention will be apparent from the following detailed description of one embodiment, by way of preferred example only, taken in conjunction with the accompanying drawings.

On the drawings:

Figure 1 is a perspective view of a flat sheet blank used for forming an adjusting sleeve according to the present invention and showing a rolled sleeve in dotted outline superimposed on the blank;

Figure 2 is a top plan view of a finished adjusting sleeve or turnbuckle barrel as formed from a blank shown in Figure 1;

40 Figure 3 is a side elevational view of an adjusting sleeve assembly utilizing a sleeve such as shown in Figure 2 and showing portions of connected members extending from the ends of the sleeve;

45 Figure 4 is a sectional view taken along line IV—IV of Figure 3 and showing the adjusting sleeve and one clamp in end elevation.

As shown on the drawings:

50 In Figure 3 is shown an adjustable sleeve or turnbuckle assembly and including an adjusting sleeve or turnbuckle barrel 11 and a pair of split clamps 12—12 on the respective end portions of the tube 11. Portions of two members 14 and 15, having right-hand and left-hand screw

threads, respectively, are threadedly inserted into the opposite ends of the sleeve 11 with their threads engaging with the respective right-hand and left-hand internal threads 16 and 17 of the sleeve.

The clamps 12 may be of any suitable construction. As shown herein, each clamp comprises a longitudinally split substantially annular bight portion 18 with a pair of spaced opposed outwardly extending parallel ears or clamping flanges 19-19 formed at the peripheral ends of the bight portion. The ears 19-19 are provided with coaxial bolt apertures (not shown) for receiving a headed adjusting bolt 20 to span a gap or split 21 between the opposed ears. A locking washer 22 and an adjusting nut 24 are positioned on the unheaded end of the bolt 20, for cooperation therewith to vary the width of the gap 21 for varying the peripheral length of the bight portion 18.

According to the present invention, means are provided for substantially increasing the clamping effect of the sleeve assembly 10 without reducing the strength of the sleeve 11. For this purpose, a pair of spiral or helical open-ended slots 25-25 are formed in the respective end portions of the sleeve 11 with the screw pitch of the helical slots being at least four times the diameter of the sleeve and herein shown as approximately eight times the diameter. The sleeve 11 is preferably at least four times as long as its outside diameter and is herein shown as about five times its diameter in length. This simple but highly important improvement in a slotted end adjusting sleeve provides several substantial advantages. A somewhat longer slot can be provided in the same length of slotted end portion of the sleeve to give greater resiliency to the end portion to produce a superior clamping effect without reducing the strength of the sleeve. Furthermore, the clamp 12 can be placed in any radial position on the slotted end portion without reducing the locking effect in contradistinction to a sleeve having a straight longitudinal slot in which the clamp split must be placed over the slot in order to attain the maximum clamping effect.

In an adjusting sleeve utilizing a straight longitudinal slot, the tendency of the slotted end portion is to hinge about a line substantially diametrically opposite the slot to give an inferior wrap-around about the connected member. In this invention, the slotted end portion will wrap about the connected member in a superior manner partially because of the increased length of the slot and increased resiliency of the end portion and partially since the material of the end portion will tend under the torsional stresses set up to hinge about the inner end of the helical slot. This pivoting of the material about the inner ends of the slot provides a wedging effect between the threads of the tube and the threads of the connected members instead of a mere straight pressure frictional engagement therebetween as is the case with a straight-slotted tube. Thus, the clamping effect is substantially increased while the clamping effort or force required is decreased.

Since the clamps may be placed in any radial

position on the slotted end portions, the assembly time of adjusting sleeve assemblies according to this invention is substantially decreased and the cost in mass production thereby reduced.

Because of the simplicity of the construction of the sleeve, it can be manufactured with equal ease from flat sheet stock or tubular stock. The adjusting sleeve shown in the drawings is produced from flat sheet stock by first forming a flat sheet blank 26 in a punch-press or the like in the exact size needed for rolling the finished tube 11 about a mandrel (not shown). It will be noted that the flat blank 26 is formed with opposite side recesses or cutouts 27-27 and 28-28 on respective opposite sides thereof. When the finished sleeve 11 is rolled from the blank 26, the opposing cutouts 27 and 28 at each end of the rolled tube form the helical slots 25 with opposite central portions 29 and 30 of the side edges in opposed abutted relation. The abutted central edges 29 and 30 may then be fixedly secured, as by welding at 31, and the internal threads 16 and 17 then formed therein by tapping operations. It will be noted that the cutouts 27 and 28 are initially formed with straight defining edges in parallel diagonal or oblique relation so that the resultant slots 25 will form true helices along the surface of the cylindrical tube 11.

From the above description, it will be readily understood that the present invention provides a substantially improved adjusting sleeve or turnbuckle assembly having helical end slots which may be formed as easily as conventional adjusting tube assemblies while achieving a substantially superior clamping efficiency.

It will be understood that modifications and variations may be effected without departing from the scope of the novel concepts of the present invention.

I claim as my invention:

An adjusting sleeve assembly for adjustably securing a threaded member, comprising an elongated tube, said tube having a helical open-ended slot in one end portion, a split clamp disposed over the slotted end portion of the tube and having a split bight portion encircling the tube, means for contracting the periphery of said clamp, said tube having screw threads formed in the slotted end portion engaging the threads of said threaded member, whereby tightening of said means induces a wedging gripping action between the threads of the tube and said threaded member in response to contraction of the clamp periphery causing contraction of the periphery of the slotted end portion of the tube.
